DOOR LOCK

Walter R. Schlage, Burlingame, Calif.; Anna Schlage, executrix of said Walter R. Schlage, deceased, assignor to Schlage Lock Company, San Francisco, Calif., a corporation of California

Application July 23, 1945, Serial No. 606,580

4 Claims. (Cl. 292—169)

1

This invention relates to a door lock especially adapted for bathrooms, lavatories and the like where it is desirable to lock the door from the inside only, and further to a lock which is adapted for installation in thin doors.

The object of the present invention is generally to improve and simplify the construction and operation of a lock of the character described; to provide a lock in which the spindle and the knobs carried thereby are adapted to be dogged against rotation; to provide a door lock having a tubular spindle with a rollback member formed thereon which cooperates with a retractor plate to retract a latch bolt; to provide a dogging mechanism which is mounted within the tubular spindle and which is operated by a push and a pull button projecting through the face of the inner knob, said button when pushed inwardly causing the dogging member to enter an opening in the retractor plate and thereby dog the spindle and knobs against operation; to provide a friction member for normally retaining the dogging member and actuating button either in dogging or released position; and further, to provide means for releasing the dogging member either by pulling outwardly on the push button or by depressing the latch bolt or by insertion of an emergency key through the outer knob.

The door lock is shown by way of illustration in the accompanying drawings, in which:

Fig. 1 is a horizontal longitudinal section showing the lock installed in the door;

Fig. 2 is a vertical section taken on line II—II of Fig. 1;

Fig. 3 is a view similar to Fig. 1 showing a modified form of the invention;

Fig. 4 is a perspective view of the retractor plate and the latch bolt carried thereby;

Fig. 5 is a perspective view of the push and pull button together with the dogging mechanism actuated thereby;

Fig. 6 is a perspective view of the friction spring;

Fig. 7 is a perspective view of the dog releasing mechanism actuated by an emergency key; and

Fig. 8 is a side elevation of an emergency key.

Referring to the drawings in detail, and particularly Figs. 1 and 2, A indicates a door in one edge of which is cut or otherwise formed a rectangular-shaped horizontally disposed opening such as indicated at B. The opposite sides of the opening are covered by side plates 2 and 3 which are secured to the door in any suitable manner and each plate is provided with an outwardly

2

extending bearing hub 4 provided for the reception and support of a tubular spindle 5.

Insertable through the outer end of the opening B is a U-shaped frame which consists of a pair of legs 6—6, the inner ends of which are connected by an end section 7 while the outer ends are bent outwardly to form a pair of lugs 8—8. A latch bolt guiding plate 9 covers the lugs and as both the lugs and the plate are perforated, screws 10 may be inserted to secure them in place.

A retractor plate 11 is slidably mounted between the legs of the U-shaped frame. Both legs are slotted as at 12 for a portion of their length and as the lug 14 is formed on each side of the retractor plate and extends into the slots, it is apparent that the retractor plate is supported and guided by the legs of the U-frame and as a latch bolt 15 is secured on the outer end of the retractor plate and extends through the latch-bolt guiding plate, additional support and guidance is provided.

The retractor plate and the latch bolt 15 normally assume the extended position shown in Figs. 1 and 2 due to the pressure of a compression spring 16 interposed between the inner end of the retractor plate and the end member 7. Two openings are formed in the retractor plate as indicated at 17 and 18. The purpose these openings serve will hereinafter be described.

The tubular spindle carries an outer knob 19 and an inner knob 20 and they may be permanently secured thereon in any suitable manner. The spindle is slotted from end to end as indicated at 21 and this slot forms a guide for a plate 22 which is mounted within the spindle. One end of the plate terminates in the dog 23, one face of which is cam-shaped as shown at 24 and a cooperating cam-face 24a is formed in the opening 17 of the retractor plate. A push or pull button 25 is attached to the opposite end of plate 22 and this button extends through the face of the inner knob 20. A bow-shaped flat spring 26 (see Figs. 1 and 6) is carried by the plate and engages the inner surface of the spindle, the springs serving the function of frictionally resisting movement of the plate and button so as to retain the dogging member either in dogging or released position.

In actual practice if a person enters a bathroom, the door of which is equipped with a door lock such as here shown, and desires to lock the door, all that person has to do is to push the button 25 inwardly. Such inward movement of the button and the plate 22 causes the dog 23 to

enter the opening 17 of the retractor plate and thereby dogs the spindle against rotation by either of the knobs. For instance, if a person should grasp the outer knob and attempt to rotate it, that person would find the knob incapable of rotation as any attempt to rotate the spindle by means of the knob would be stopped by the dog 23 engaging one or another of the side walls 17a or 17b of the opening 17. On the other hand, if the person occupying the room desires to open the door, that person will merely pull the button outwardly, thus withdrawing the dog 23 from the opening 17, thereby leaving the spindle free to be rotated by either the inner or the outer knob.

The spindle has a rollback member 28 formed thereon by cutting a cross slot 29 partially through the spindle. This rollback passes through the opening 18 formed on the retractor plate and engages the flat surface 18a formed at one end of said opening. When the spindle is rotated, the rollback 28 engages this flat surface and as such causes retraction of a retractor plate and latch bolt, but when the spindle or the knob by which it is rotated is released, the compression spring 16 restores all parts to assume normal position.

It could happen that a person, not familiar with the function of the lock, or that a child playing with it, might open the door, then depress the button and shut or slam the door closed. If that should happen, the inclined face of the latch bolt 15 would engage the striker face of the door frame and thus cause depression of the latch bolt. Such depression would cause the cam face 24a to engage the cam face 24 on the dog 23, and thus force the dog out of the opening 17 to assume the position shown in Fig. 1. Thus the dog may be released either by depression of the latch bolt 15 or by pulling outwardly on the button 25.

Instances are known where a child has entered a bathroom or where a person occupying it has fainted or become otherwise incapable of opening a door after entering and locking it. In such instances it is desirable to provide an emergency key whereby the door may be opened from the exterior. To accomplish this the mechanism shown in the modification of Fig. 3 is employed. This mechanism consists of a plate 30 mounted within the spindle and in the outer end thereof.

This plate is slidably mounted in the keyway of the spindle and is normally held in the position shown in Fig. 3 by a spring 31. A pin or lug 32 is formed on the inner end of the plate. An opening 34 is formed in the outer knob in alignment with the plate. A key 35 in the form of a pin such as shown in Fig. 8 may be inserted in this hole and when the key is pushed inwardly it pushes the plate 30 inwardly, thus causing the pin or lug 32 to enter the opening 17 of the retractor plate and push the dog 23 out of engagement therewith. The moment the key is removed, the plate 30 returns to normal position and as the spindle is now undogged, the door may be opened.

The lock as a whole may, of course, be used without the emergency key and releasing mechanism and that form of lock is shown in Figs. 1 and 2, but whenever desired, the form of lock shown in Fig. 3 may be employed, and while this and other features of the invention have been more or less specifically described and illustrated, it should be understood that changes may be resorted to within the scope of the appended claims and that the materials and finish of the several parts employed may be such as the experience

or judgment of the manufacturer may dictate or varying conditions or uses may demand.

Having thus described my invention, what I claim and desire to secure by Letters Patent is:

5 1. In a lock, a latch bolt, a retractor plate secured to the latch bolt, a rotatable tubular spindle passing through the retractor plate and having a rollback member formed thereon which is engageable with the retractor plate to retract the latch bolt when the spindle is rotated, a dog slidably mounted within the spindle and engageable with the retractor plate to dog the spindle against rotation, and means on the retractor plate to undog the spindle when the latch bolt is depressed.

10 2. In a lock, a latch bolt, a retractor plate secured to the latch bolt, a rotatable tubular spindle passing through the retractor plate and having a rollback member formed thereon which is engageable with the retractor plate to retract the latch bolt when the spindle is rotated, a dog slidably mounted within the spindle and engageable with the retractor plate to dog the spindle against rotation, means on the retractor plate to undog the spindle when the latch bolt is depressed, an inner knob on the spindle, and a push and pull member projecting through said knob, said member being secured to the dog so as to impart movement to the dog to dog or undog the spindle.

15 3. In a lock, a latch bolt, a retractor plate secured to the latch bolt, a rotatable tubular spindle passing through the retractor plate and having a rollback member formed thereon which is engageable with the retractor plate to retract the latch bolt when the spindle is rotated, a slot formed in the spindle and extending longitudinally thereof, a plate slidably mounted in the spindle and guided by said slot, a dog on one end of the plate and a push and pull member on the opposite end of the plate and extending through an inner knob secured on the spindle, said member adapted to move the dog into or out of engagement with the retractor plate to undog or dog the spindle against rotation.

20 4. In a lock, a latch bolt, a retractor plate secured to the latch bolt, a rotatable tubular spindle passing through the retractor plate and having a rollback member formed thereon which is engageable with the retractor plate to retract the latch bolt when the spindle is rotated, a slot formed in the spindle and extending longitudinally thereof, a plate slidably mounted in the spindle and guided by said slot, a dog on one end of the plate and a push and pull member on the opposite end of the plate and extending through an inner knob secured on the spindle, said member adapted to move the dog into or out of engagement with the retractor plate to undog or dog the spindle against rotation, and means actuated by depression of the latch bolt for moving the dog away from dogging position.
